(57) **CLAIM**

The ornamental design for a convertible scarf to mask garment, as shown and described.

DESCRIPTION

FIG. 1 is a front perspective view of the convertible scarf to mask garment showing the new design.

FIG. 2 is a front view thereof.

FIG. 3 is a rear view thereof.

FIG. 4 is a right view thereof.

FIG. 5 is a left view thereof.

FIG. 6 is a top view thereof.

FIG. 7 is a bottom view thereof.

FIG. 8 is a front view of the convertible scarf to mask garment, shown as worn in the scarf configuration.

FIG. 9 is a front view of the convertible scarf to mask garment, shown as worn in the mask configuration; and,

FIG. 10 is a perspective view of the convertible scarf to mask garment, shown in a flattened, or unfolded, position. The broken lines shown in the article depict stitching and form no part of the claimed design. The broken lines showing the wearer in FIGS. 8 and 9 depict environment and form no part of the claimed design.
